Attorneys.

UNITED STATES PATENT OFFICE.

JOHN J. DONOVAN, OF BOSTON, MASSACHUSETTS.

DRINKING-FOUNTAIN.

1,283,110.

Specification of Letters Patent. Patented Oct. 29, 1918.

Application filed April 12, 1918. Serial No. 228,129.

To all whom it may concern:

Be it known that I, JOHN J. DONOVAN, a citizen of the United States, residing at Boston, in the county of Suffolk and State 5 of Massachusetts, have invented new and useful Improvements in Drinking-Fountains, of which the following is a specification.

This invention has for its object to provide a drinking fountain for use in schools, 10 industrial establishments and other public places, and more especially to provide a fountain which is sanitary and unlikely to spread disease.

15 As a result of prolonged investigation and study, it has been determined by bacteriological examination of certain fountains now in use that, where the water jet is directed vertically, it frequently happens that the 20 water carries with it the germs which have been deposited upon the fountain with the saliva of the previous user. This occurs especially in the cases referred to, because the user places his lips upon some portion of the 25 fountain, notwithstanding the height of the jet.

To overcome this danger to the public, I have produced a fountain in which the jet of water is directed upwardly and laterally 30 to insure that it shall not return again upon the nozzle. Then, to prevent the user from placing his lips too closely to the nozzle, I form the latter with a dome which protects the nozzle, and which is itself continuously 35 washed by water separate from that issuing from the nozzle. These and other features which mark my improved fountain are explained more at length in the following specification and are particularized in the 40 claims.

On the drawing,—

Figure 1 represents in front elevation a fountain embodying my invention.

Fig. 2 represents a plan view of the same.

45 Fig. 3 represents an inverted plan view, to show the valve which controls the supply of water to the several ports or orifices.

Fig. 4 represents a section on the line 4—4 of Fig. 1.

50 Fig. 5 represents a similar section, and in addition shows the valve and the top screw in section.

Fig. 6 represents a cross section on the line 6—6 of Fig. 4.

55 Figs. 7 and 8 represent respectively the top screw and the valve.

Referring to said drawings,—the fountain there shown consists of a dome-shaped head which may be screwed upon the end of a pipe 10. The dome 11 is hollow, except as 60 hereinafter described, and is cast upon a base 12 which is interiorly threaded to receive the pipe 10. Across the bottom of the dome at its juncture with the base, there is a transverse web or partition 13, and across 65 the dome there is a second web or partition 14, between which a water chamber 15 is thereby formed. This chamber communicates with the interior of the base through a valve screw 16 having a longitudinal aperture 17 and transverse ports 18 close to the head 19 of the screw. By adjusting the valve 16 in relation to the web 13, the ports 18 may be partially or entirely opened or 70 closed.

75 Extending from the web 14 to the top of the dome, there is a core or pillar 20 which is swelled forwardly as at 21. The pillar swells outwardly at its upper end and merges in the side wall of the dome to provide an increased thickness of stock under the top and the middle of the dome. A duct or jet aperture 22 is formed in the forwardly swelled base of the pillar which thereby constitutes the jet nozzle, and this duct is inclined so that the jet is directed upwardly and forwardly at an acute angle to the vertical, the top of the jet being in front of the fountain. The dome has in its front an elongated vertical slot or opening 23, which starts at the partition 14 and terminates below the top of the dome to leave a shelf or overhang 24 which is directly above and covers the end of the aperture 22, as clearly shown in Figs. 2 and 4.

95 Through the pillar 20, a duct 25 extends from the water chamber 15 to a central cylindrical recess or cavity 26 in the top of the dome to permit a stream of water, independent of that issuing from the main nozzle, to flow for continuously washing the exterior surface of the dome. A reducing valve, in the form of a screw 27 is screwed into the upper end of the duct 25, and it has a beveled head 127 which nearly fills the recess and leaves a narrow annular passage between its edge and the encircling wall of the recess. The lower end of the screw has a reduced central opening 28 communicating with lateral ports 29 for delivering 100 water from the central duct to the bottom of the recess 26. Thus a small stream of water 105

is permitted to flow from the recess and to cover the exterior surface of the dome for constantly washing it. The screw is sufficiently depressed within the cavity or recess 5 to cause the head to be submerged in the pool of water therein.

The fountain is provided with an "anti-squirt" feature, so that a mischievous person cannot, by placing his finger on the nozzle, spray the water laterally. It will be observed that a port 30 leads laterally from the nozzle to the interior of the dome. When the jet of water issues normally from the nozzle, substantially none escapes from 10 the port, but, if the jet aperture be closed, the water will issue into the interior of the dome. The top surface of the partition 14 slopes downwardly and forwardly toward the opening 23. The interior of the dome 15 and the surface of the partition 14 may be constantly flushed with water by providing ports 31 through the top of the dome and spaced about the recess or cavity 26. These ports also prevent a person imbibing water 20 from the top as air would be drawn into the mouth and prevent free suction.

By reason of the construction which I have thus illustrated and described, a person cannot place his lips on the nozzle since 30 it is impossible of access, and there is no chance of saliva being deposited thereon. The top of the jet being laterally remote from the fountain, there is no occasion for resting any portion of the face on any part 35 of the latter, and, since the dome is constantly flushed with water, not only is it kept cleaner, but the fact that the face will be wetted in case it comes in contact with the dome, acts as a deterrent to touching the 40 dome. The nozzle is located well above the partition 14, so that there is no danger of any water flowing along the surface of the latter being carried upward by the jet. The whole fountain is constantly washed by an 45 ever-flowing stream, which is independent of the drinking-jet. It is intended, of course, that the drinking-jet shall pass through the opening 23 in the dome without impingement on the walls thereof.

50 The regulating valve, which controls both the jet and the washing stream, is located within the fountain, and cannot be tampered with so long as the fountain is in place since at such time it is inaccessible.

55 Having thus explained the nature of my said invention and described a way of making and using the same, although without attempting to set forth all of the forms in which it may be made or all of the modes of 60 its use, what I claim is:

1. A bubbling fountain comprising a nozzle having an inclined jet aperture, and a stationary dome covering the delivery end of the nozzle, but located out of the path 65 of the jet.

2. A bubbling fountain comprising a nozzle having an inclined aperture, a dome covering the delivery end of the nozzle, and means for supplying a washing stream to the surface of the dome.

3. A bubbling fountain comprising a nozzle having an inclined jet aperture, a stationary dome inclosing and covering the delivery end of said nozzle and having an opening through which the jet issues without 70 impingement against the walls thereof.

4. A bubbling fountain comprising a dome having an opening in its front wall, an inclined nozzle within the dome arranged to direct a jet of water upwardly and forwardly through said opening, and means for supplying a second stream of water to wash the exterior of the dome.

5. A bubbling fountain comprising a dome having an opening in its front wall, 85 an inclined nozzle within the dome arranged to direct a jet of water upwardly and forwardly through said opening, means for supplying a second stream of water to wash the exterior of the dome, and a single regulating 90 valve for controlling the jet and the stream.

6. A bubbling fountain comprising a head having an opening in its front wall, an inclined nozzle within the head arranged to direct a jet of water upwardly and forwardly through said opening, means for supplying a second stream of water to wash the exterior of the head, and a regulating valve, concealed within the fountain and inaccessible when the fountain is in place, for 100 regulating said jet and said stream.

7. A drinking fountain comprising a dome having a central core or pillar, and an opening in one side thereof, a nozzle located within the dome and arranged to deliver a jet through said opening, a duct leading through said pillar for supplying water to the top of the dome to flush the exterior thereof, and means for supplying water to said nozzle and duct.

8. A bubbling drinking fountain comprising a dome-shaped head having a transverse web forming a water chamber therebelow, a nozzle arranged to deliver water upwardly from said chamber, and a duct leading from the said chamber to the top of the head for supplying water to flush the exterior thereof.

9. A bubbling drinking fountain comprising a hollow head having a transverse web forming a water chamber therebelow, a central core or pillar above the said web and having a duct communicating with the water chamber for the emission of water upon the surface of the head, and a nozzle for delivering a jet of water from said chamber.

10. A bubbling drinking fountain comprising a hollow head divided horizontally by a web and having a central apertured pillar extending from the web to the top of 130

the head, a jet duct through said web, and a cavity or recess at the top of the head communicating with the aperture in the pillar.

11. A bubbling drinking fountain comprising a head open in the front, a nozzle within the head arranged to deliver a jet upwardly and outwardly through said opening and overhung by a portion of the head, and a duct, independent of the nozzle, for 10 delivering a stream upon the exterior of the head.

12. A bubbling drinking fountain comprising a head having an opening on one side and a top central cavity, a nozzle within 15 the head arranged to deliver a jet through said opening, a duct leading to said cavity, and a reducing screw valve submerged in the cavity and screwed in the end of the duct.

20 13. A bubbling drinking fountain comprising a head having a hollow base for attachment to a supply pipe, a hollow upper portion, a transverse web above the base at the lower end of the head forming a water 25 chamber therebelow, an opening in the side wall of the head, a nozzle within the head and having its jet aperture extending through the web, a longitudinally apertured

central core extending from the web to the top of the head, and a central cavity at the 30 top of the head, a regulating valve for controlling the supply of water from the base to said chamber, and a reducing valve in said cavity screwed into the upper end of the aperture in said core. 35

14. A bubbling drinking fountain comprising a hollow head, provided with a side opening, an inclined jet nozzle within the head for delivering a jet laterally and upwardly through said opening, and means 40 for flushing the interior and exterior of said head with water independent of that issuing from the jet nozzle.

15. A bubbling drinking fountain, comprising a hollow head, a central core therein 45 having a duct for the emission of water on the exterior surface of the dome, a nozzle arranged to deliver a jet of drinking water laterally from the head, and one or more ducts leading from the hollow head and 50 terminating at the top of the head in proximity to the first-mentioned duct.

In testimony whereof I have affixed my signature.

JOHN J. DONOVAN.
